(57) **CLAIM**

The ornamental design for an ultrasound robotic arm as shown and described.

DESCRIPTION

Fig. 1.1 is a front perspective view of the ultrasound robotic arm;

Fig. 1.2 is a front perspective view thereof;

Fig. 1.3 is a front view thereof;

Fig. 1.4 is a left side view thereof;

Fig. 1.5 is a right side view thereof;

Fig. 1.6 is a top view thereof; and

Fig. 1.7 is a bottom view thereof.

The broken lines illustrate environment and form no part of the claimed design.
